WHEEL

Isaac M. Laddon, Dayton, Ohio, assignor to Bé-
dix Brake Company, South Bend, Ind., a cor-
poration of Illinois

Application November 21, 1927
Serial No. 234,616

4 Claims. (Cl. 188—78)

This invention relates to wheels, and is illus-
trated as embodied in part of the landing gear
of an airplane, which landing gear includes a
wheel having a novel brake and shock absorbing
structure.

An object of the invention is to provide the
wheel with means for absorbing the shock of
landing, preferably housed within the outline of
the wheel to give a streamline effect, and which
10 wheel is provided with a brake including a fric-
tion device encircling the shock-absorbing means
and which is expansible against an outer cyl-
indrical braking surface carried by the wheel.
Thus the parts are all nested within one another,
15 both brake and shock-absorbing means being ar-
ranged within the wheel outline.

Various other features of novelty relate to
structural improvements in the brake, especially
those adapting it for use on an aeroplane wheel,
20 and including a novel wear adjustment, an im-
proved fluid-power operating means, a new ar-
rangement of links or the like to control the ex-
pansion of the brake, and other desirable par-
ticular constructions which will be apparent from
25 the following description of several illustrative
embodiments shown in the accompanying draw-
ings, in which:

Figure 1 is a side elevation, looking from the
inner side, of one wheel of an aeroplane and of
30 the associated parts of the landing gear;

Figure 2 is a vertical section through the parts
of Figure 1, on the line 2—2 of Figure 1;

Figures 3, 4, and 5 are sections through the
shock-absorbing means, taken respectively on
35 the lines 3—3, 4—4, and 5—5 of Figure 2;

Figure 6 is a partial elevation, looking in the
direction of the arrows 6—6 in Figure 2;

Figure 7 is an elevation corresponding to Fig-
ure 1, but showing a modification;

Figure 8 is a vertical section through the modi-
fication of Figure 7, on the line 8—8 of Figure 7;

Figure 9 is a section through the hydraulic
brake-operating mechanism, on the line 9—9 of
45 Figure 7;

Figure 10 is a partial elevation of the inter-
engaging parts of shock-absorbing means, look-
ing in the direction of the arrows 10—10 of Fig-
ure 7;

Figure 11 is an elevation, corresponding to Fig-
ure 1, of another modification;

Figure 12 is a vertical section through this
modification, on the line 12—12 of Figure 11;

Figure 13 is an inside or bottom plan view of
55 the connected ends of the shoes making up the

brake friction means of Figure 11, looking in the
direction of the arrows 13—13 of Figure 11;

Figure 14 is a section through part of the
shock-absorbing means of this modification, on
the line 14—14 of Figure 11; 60

Figure 15 is a section through one of the brake
shoes of Figures 11 and 13, on the line 15—15 of
Figure 13;

Figure 16 is a vertical section corresponding to
Figure 2, but showing a modification of the 65
shock-absorbing means;

Figure 17 is an elevation of the inner face of
the shock-absorbing means of Figure 16; and

Figure 18 is a partial section through the shock-
absorbing means, on the line 18—18 of Figure 16. 70

In the arrangement of Figures 1—6, the wheel
comprises an outer disk 20 and an inner disk 22,
secured to opposite sides of a flange 24 formed
on a hub 26, and secured at their outer edges to
the sides of a rim 28. Disk 22 is dished, so that 75
substantially the entire space within the wheel is
unobstructed, and in the form here illustrated
the disk engages the bottom of rim 28, which is
of the drop-center type. Thus the inner face of
disk 22, near its outer edge, is internally-cyl- 80
indrical and serves to provide a braking surface.

Within the dished disk 22 is arranged novel
shock-absorbing means, preferably of the hy-
draulic type, and which absorbs the vertical 85
shock when the aeroplane lands. This means
includes a cylinder 30, shown as an integral ex-
tension of a spindle 32 on which the hub is
mounted. A piston 34 within the cylinder is
connected to a slide 36 secured to the aeroplane
proper in any desired manner. Cylinder 30 is 90
filled, through a passage 38 and through a hol-
low piston rod 40, with oil or other liquid which
is forced, in landing the aeroplane, from below to
above piston 34 through openings 42.

An important feature of the invention relates
to the arrangement of a brake friction device
for engagement with the braking surface of disk
22, in such a manner as to encircle the above-
described shock-absorbing means without inter- 100
fering with it. I prefer to use a somewhat flex-
ible band 44, anchored on a flange 46 of the
cylinder 30 by a pivot 48.

Band 44 is operatively connected at its other
end to a thrust link 50, pivoted at one end to the
band by a pivot 52 extending crosswise of the 105
band, and carried by a pin 54 mounted in the end
of the link 50. The other end of the link 50 is
pivotally mounted on the lower end of a plunger
56, in such a manner that it can swing about the
axis of the plunger. 110

Plunger 56 is guided for lengthwise movement in a bracket 58 secured to the flange 46, and in one or more guides 60 secured to or formed in the material of the cylinder 30. The upper end 5 of plunger 56 forms a piston fitting in a small hydraulic cylinder 62 (Figure 1) connected by a suitable flexible conduit (not shown) to an operating cylinder and piston adjacent the pilot's seat.

10 In order to permit adjustment of the brake, the band 44 is made in two or more sections, a toothed clamp plate 64 riveted to the end of one section being clamped by a bolt or the like 66 to the end of the adjacent section. Links 68 pivoted to cylinder 30 serve to control the expansion and contraction of the band. Each link is shown with a head co-operating with a fitting 70 pivoted to the band 44, to confine between them a coil spring 72 which urges the band away from the 15 brake drum surface on disk 22. Stampings 74 may be secured to disk 22 on opposite sides of band 44 to aid in housing it and to protect it.

The shock absorber as shown is intended to function as the sole shock absorbing device, not 20 requiring any other supporting springs although of course, the tires on the wheels cooperate with the oleo shock absorber. After the oleo shock absorber has taken the relatively large shock of landing, either the ring spring (shown on Figure 25 12 at 90) or the rubber blocks (shown on Figure 16 at the top of the piston tube) will serve to provide the necessary resiliency for taxiing. The utilization of the shock absorber as a supporting spring for the airplane is considered preferable 30 by me. However, if desired other types of springs could also be provided to give additional support.

The construction of Figures 7—10 differs from that described above, in that there are three links 40 68 instead of two, and there is a horizontal hydraulic cylinder 80 formed in the flange 46, and containing a piston 82 connected by a link or connecting rod 84 to the end of band 44. Figure 10 shows a detail of the shock-absorbing means in the attachment of a block 86 forming 45 part of the slide on the lower end of part 36 which embraces the sides of the cylinder 30. As shown in dotted lines, a block 88 of rubber may be arranged to transmit the load to the 50 wheel when piston 34 reaches its lowermost position,—i. e., when the aeroplane is on the ground.

In Figures 11—15, the load is taken when on the ground by a spring 90 in the cylinder 30, and coil springs 92 replace the links 68. The 55 band 44 is replaced by two shoes 94 and 96, connected by a floating pivot 98. Shoe 94 is anchored to cylinder 30 by a pivot 100, and shoe 96 is operatively connected by a link or connecting rod 102 with a piston 104 in a cylinder 60 106 detachably bolted to the cylinder 30. Each shoe may be formed, as illustrated in Figure

15, of two L-section steel or duraluminum stampings riveted or otherwise secured back to back to form a T-section shoe, to which the lining is riveted or otherwise secured.

As shown in Figures 16—18, the hydraulic shock-absorbing means may include a tapered plunger 110, carried by the cylinder 30 and extending into a central opening in piston 34, and serving gradually to throttle the flow of liquid. 80

While several illustrative embodiments have been described in detail, it is not my intention to limit the scope of the invention to those particular embodiments, or otherwise than by the terms of the appended claims. 85

I claim:

1. Aeroplane landing gear comprising a wheel having an internally-cylindrical braking surface, a shock-absorbing device including vertically-movable parts, one of which moves with the wheel, and which are encircled by said surface, a brake friction device encircling the shock-absorbing device and expansible against the braking surface, and means for operating the brake friction device carried by a part of the shock-absorbing device. 90

2. Aeroplane landing gear comprising a wheel having an internally-cylindrical braking surface, a shock-absorbing device including vertically-movable parts, one of which moves with the wheel, and which are encircled by said surface, a brake friction device supported by and encircling the shock-absorbing device and expansible against the braking surface, and a fluid-power operator for the brake friction device which is carried by the part of the shock-absorbing device which moves with the wheel. 100

3. Aeroplane landing gear comprising a wheel having an internally-cylindrical brake drum surface, a shock-absorbing device including vertically-movable parts encircled by said surface and one of which moves with the wheel, a brake friction device supported by and encircling the shock-absorbing device and expansible against said brake drum surface, and means connected to one of the parts of the shock-absorbing device and arranged to control the position of the brake friction device. 115

4. Aeroplane landing gear, comprising a wheel having an internally cylindrical brake surface; a shock absorber device having a cylinder and a piston movable therein, one of which moves with the wheel, and which are both encircled by said surface; a brake friction device supported by and encircling the shock absorbing device and expansible against the braking surface; and a fluid power operator for the brake friction device comprising a cylinder and a piston in the cylinder, said cylinder being arranged substantially parallel with and secured to the shock absorbing cylinder. 125

ISAAC M. LADDON.
